UNITED STATES PATENT OFFICE.

LOUIS T. PYOTT, OF PHILADELPHIA, PENNSYLVANIA, ASSIGNOR OF ONE-HALF TO DANIEL E. WATERS AND WILLIAM G. VERNON, OF SAME PLACE.

TRUCK FOR STREET-RAILWAY CARS.

SPECIFICATION forming part of Letters Patent No. 544,417, dated August 13, 1895.

Application filed March 12, 1895. Serial No. 541,444. (No model.)

To all whom it may concern:

Be it known that I, LOUIS T. PYOTT, a citizen of the United States, residing at Philadelphia, in the county of Philadelphia and State of Pennsylvania, have invented certain new and useful Improvements in Trucks for Street-Railway Cars; and I do declare the following to be a full, clear, and exact description of the invention, such as will enable others skilled in the art to which it appertains to make and use the same, reference being had to the accompanying drawings, and to the letters of reference marked thereon, which form a part of this specification.

My improvement consists in arranging and applying a truck to a street-railway car independent of the car in its construction, so that a truck of this kind may be interchangeably used under different cars of the same construction or under different constructions, such as summer or open cars and winter or closed cars, and as the two kinds of cars are now generally in use by street-railway companies it is a matter of much importance to be able to use both sets of cars on one set of trucks, thereby greatly lessening the original outlay and also greatly facilitating the interchange of a damaged body to another truck, or vice versa. This construction is a great improvement over the present form, where the car and its truck are built together and inseparable, my truck being entirely separate from the car and capable of removal without displacing any part of the car's bracings, ties, or any other members, making the removal easily, inexpensively, and quickly. Another advantage of my improvements is that I can very readily remove the wheels and axles when they are worn, as is very frequently the case, without detaching any important members or in any way taking the truck or its car apart. I attain these objects by the mechanism illustrated in the accompanying drawings, in which—

Figure 1 is a side elevation of the truck. Fig. 2 is a plan view of the truck. Fig. 3 is a section on line *a b*, Fig. 4, of one of the corrugated central connection-plates. Fig. 4 is an elevation of one of the corrugated central

connection-plates. Fig. 5 is a rear elevation of the axle-box. Fig. 6 is an elevation of the pedestal side of the axle-box. Fig. 7 is an elevation of the cover side of the axle-box. Fig. 8 is a plan view of the axle-box.

Similar letters refer to similar parts throughout the views.

I employ the usual wheels A and axles B as ordinarily used under street-cars, and at the usual distance apart, center to center; but the bearings C are inserted into a new form of axle-box D, the axle box having an opening at the side E, the opening being closed by a cover F, preferably hinged at the bottom G and secured at the top by a yoke-bolt H, the back of the axle-box D being formed with an opening d, which permits the insertion of the axle B, through the openings E and d, to its position in the bearing C or its removal therefrom without in any manner disturbing the axle-box D from its fastenings or its removal from the truck. The axle-boxes D are securely fastened by rivets or bolts e to two straight longitudinal bars J, located below them, and which embrace each side of a lower lug j, cast integral with the axle-box D, and which also serves as a distance-block between the two bars J of the truck side frame. The bars J unite the axle-boxes D in positive and fixed distance apart longitudinally, and each bar J, being an integral piece, is not subjected or liable to fracture, as in the ordinary constructions of trucks, and is less expensive than when joined to pedestals by bolts or rivets, and also avoids all liability to work loose and to rattle and jar.

The bars J are extended beyond the axle-boxes D to enable the attaching of brakes, fenders, and the cross-ties K, which control the parallelism of the two sides of the truck. It will be observed that in my construction of a truck the axle-boxes are immovably secured upon their frames, so that the wheels and frames always go in unison, and when the wheels meet imperfections of track or obstructions the frames rise and fall with the wheels, and if the truck was rigidly constructed throughout—that is, one side rigid with the other side—the frame would have to

rack and twist to allow the wheels to find and rest upon uneven rails or the rail contact and adhesion would be imperfect, tending to make the motors slip the wheels, producing flat spots, and uselessly expending power. To overcome such a defect I make the two sides of the truck free in their vertical movement, one as against the other, by uniting the two sides so that they are pivoted to each other, allowing of a free oscillating movement of the frames to give the wheels perfect uniform adhesion to the rails, and all to have the same contact. To accomplish this very desirable and necessary result, the side frames J J J J are connected together by two A-shaped braces L L, these braces L L having their base securely fastened by bolts or rivets to the frames J J and by brackets n, and at their connecting ends being secured to each other by a pivot-pin M, which holds one to the other laterally while permitting free radial movement. At the point of junction I interpose two interlocking corrugated plates N P. These plates N P, having their corrugations in circular lines, permit of free radial movement one on the other, while maintaining the necessary longitudinal contact to cause the two sides of the truck to advance or recede in unison, they being chambered at u to seat over the brace-frames L. Upon the A-brace frames L are motor-supports provided with spring-pockets r to secure either center-hung or over-hung motors. The ends of the truck are held laterally and parallel by cross-ties K, joined at the place of contact with the side frames J J by a single rivet or bolt m, which permits of pivotal action while securing the parallelism desired.

The side frame J J has near each end, beyond the wheels, guides w to receive brake mechanism for stopping the wheels, the guides permitting the brake-shoes to move horizontally against the wheels.

The truck propels the car by means of pedestals T T', attached to the car, and which abut against the axle-boxes D upon opposite sides. Thus by means of the axle-boxes D, being rigidly attached to the frame J all wheels are driven in either forward or backward motion, as required, through the pedestals T T'.

The axle-boxes D have on their pedestal sides tongues and grooves, or, if preferable, corrugations, to interlock with similar construction on the pedestals of the car to hold the axle-boxes and pedestals to their correct lateral position while permitting free vertical movement.

I claim as my invention—

1. In a street car truck, wheels for the truck, axles for the wheels, the axles placed in bearings inserted in axle boxes which are rigidly and unyieldingly attached to a frame suspended under them and connecting them fixedly together, and means for inserting or removing the axles from the sides of the axle boxes without removing the axle boxes from

their frame, or the separation of the frame, the truck construction being separate and distinct from the car to which it is applied, substantially as described. 70

2. In a car truck, the combination of wheels, axles for the wheels, bearings for the axles, axle boxes for the bearings securely attached to an under frame, side openings in the axle boxes for the insertion or removal of the 75 axles and the extension of the frame composed of integral bars beyond the wheels, and guides for brake shoes, substantially as described.

3. A street car truck having axle boxes rigidly attached to a suspended side frame work of integral bars, the frame work extending beyond the wheels, and the two sides of the frames connected at each outer end by a crosstie having pivotal connection for vertical radial movement with each side frame work, substantially as described. 80

4. A street car truck having on each side axle boxes rigidly secured together longitudinally, and at its central lateral connection means for radial movement, and interlocking corrugated plates to control contact and pressure for longitudinal movement, substantially as described. 90

5. In a street car truck rigid and unyielding side frames, axle boxes firmly fixed thereon, means for connecting the two sides of the truck yielding together for vertical-radial movement at the ends and the center, and supports for motors attached to the central cross-braces—substantially as described. 95

6. In a street motor car truck, rigid side frames, side opening axle boxes immovably secured thereto, and one side of each of said axle boxes engaging with pedestals from the 105 car, the truck structure being independent of the car and removable and detachable therefrom, substantially as described.

7. The combination in a street car truck of wheels, axles for the wheels axle boxes with 110 side openings and integral barframes rigidly secured to said axle boxes, substantially as described.

8. The combination in a street car truck of axles, wheels on the axles, bearings for the 115 journals of the axles, side opening boxes for the bearings, framing for the boxes rigidly attached thereto and extending beyond them, and guides on the extended ends of the framing for directing and controlling the movement of brake shoes, substantially as described. 120

9. The combination in a street car truck of wheels, axles for the wheels, bearings for the 125 axles, axle boxes with side openings for the bearings, and tongues and grooves on one side of each axle box, substantially as described.

10. The combination in a street car truck, of wheels, axles for the wheels, bearings for the axles, side opening boxes rigidly attached to the frame, and each side of the truck 130

joined to the other side with means for flexible radial movement at the point of union, substantially as described.

11. The combination in a street car truck, 5 of wheels, axles for the wheels, bearings and boxes for the axles, the boxes having side openings and being rigidly attached to the frames, and means to connect the frames laterally at their ends for pivotal movement substantially as described.

12. In a street car truck, the combination 15 of wheels, axles for the wheels, bearings and boxes for the axles, rigidly attached frames to the axle boxes, pivotal union of the frames transversely and means for interlocking at

the point of union to join the two parts of the truck longitudinally, substantially as described.

13. In a street car truck independent of the car it carries, a frame on each side unyieldingly secured to the axle boxes of that side, and means for joining the two sides flexibly at the center, and at each end, substantially as described.

In testimony whereof I affix my signature 25 in presence of two witnesses.

LOUIS T. PYOTT.
